UNITED STATES PATENT OFFICE.

THOMAS BRYAN FOTHERINGHAM AND MAE MCINTYRE, OF SEATTLE, WASHINGTON.

STREET AND STATION INDICATOR.

Application filed June 1, 1926. Serial No. 112,863.

Our invention relates to street and station indicators, designed for use on cars to indicate visibly to the passengers the names of the streets or stations, as they are approached. Its object is to inform the passengers as to the stopping places in advance, so that there may be no uncertainty as to when they should leave the car.

A further object is to do this by means which are sufficiently flexible and reliable in design to adapt the device to the variable conditions of the route followed. Other objects will appear from a study of the specification.

15 Our invention comprises an electrically actuated mechanism for advancing a web having the street or station names thereon, and means whereby such actuating means are started by hand and are automatically stopped after bringing the new name into view.

The features of our invention which are believed to be new, and upon which patent is desired, will be specifically defined by the 25 claim.

In the accompanying drawings we have shown our invention in a form of construction adapted to illustrate the principles embodied, in which, however, many of the 30 detailed parts are shown in simple types of construction, for which other designs may be substituted without changing their essential functions or their relationship in the combinations.

35 Figure 1 is a plan view of the mechanism employed, except that the name-holding web has been omitted in order to clearly show the operating mechanism.

Figure 2 is a transverse sectional elevation taken at one end of the rollers, the plane being approximately indicated by the broken line 2—2 of Figure 1.

Figure 3 is a wiring diagram.

Figure 4 illustrates control switch 48 and 45 its connected parts employed in securing and controlling the periodic advance of the name bearing web. The plane of view is indicated by the broken line 4—4 of Figure 1.

Figure 5 is a section taken on the plane indicated by the broken line 5—5 of Figure 1.

To display the street or station name, we employ a web 11, shown in Figure 2 but omitted in Figure 1. The ends of this web are secured to rollers 1 and 10 which are intermittently operated to advance the web a single name space at a time, and to reverse

the direction of movement of the web as the ends of the web are reached. The means for actuating the web is preferably a small motor of some kind. An electric motor 2 has 60 been shown for doing this.

The motor shaft 20 is connected with the web carrying rollers 1 and 10 by gear trains, these as illustrated comprising the gears and pinions numbered from 21 to 27 inclusive. 65 The gears 26 and 27, which are the final gears of the trains, are mounted loosely upon the shafts of the rollers 1 and 10. They are each in turn, secured to turn with said rollers, through clutch mechanisms. Said 70 clutch mechanisms as shown each consists of an arm 3 carried upon a sleeve 30 which is mounted upon the roll shaft to turn therewith, and to be reciprocable thereon enough to engage and disengage the arm 3 with the 75 gear 26 or 27 as the case may be. The sleeves 30 are moved into and out of engaging position by a lever 31, pivoted centrally at 32.

The lever 31 is a reversing lever and is actuated to shift the engagement of the 80 clutches, only when the direction of feed of the web is to be reversed. Normally this would be only at the ends of the run of the car and as the ends of the webs are reached. 85 The means adopted for securing such reversal will be later described.

The web 11, between the storage rolls 1 and 10, passes over guide rolls, 12 and 13, which position that part of the web carrying the name to be displayed behind a window 11^a. One of these guide rollers, 13 as shown, carries two electrical conductors in the form of bars 14 and 15, which extends lengthwise of the periphery of the roller, and overlap each other at one end. They are also angularly separated a small amount. 95

This condition is clearly shown in Figures 1 and 2.

The machine is to be placed in a street car, 100 motorbus, or railroad car where it can best be seen by the passengers, and is operated in the following manner:

Push button 57, which may be located in 105 convenient place for the conductor or motorman to press, is pressed by conductor as each street or station is approached, which energizes starting solenoid 52, which pulls plunger and closes switch 42, giving energy to the motor circuit and at suitable and later times 110 to the stopping and reversing circuits. When push-button 57 is pressed the cur-

rent of electricity flows from power line 50 through conductor 56 and small solenoid 55, which causes core 58 of the latter to open switch 6, breaking the circuit of the stopping solenoid 53, coming from switches 14 and 15.

6 Solenoids 55 and 52 are connected in series by conductor 54.

When pushbutton 57 is pressed and closes switch 42 the motor, through the gear mechanism, causes the spools 1-10 which hold the web 11 carrying the street names, to revolve and wind off one on to the other, over the guide rolls 12-13, bringing the street names into full view of passengers through 15 glass 11.

When the web 11 advances far enough to show the street name properly the motor is stopped automatically by contacts or switches 14-15 on guide roll 13 (Figure 2) coming 20 in contact with common circuit 40 and 4 or 41 (Figure 3) which energizes stopping solenoid 53, which causes plunger to open switch 42 which turns electric current off entire machine. Contacts 14-15 may be adjusted 25 closer or farther apart as necessary. Contact 14 will bridge 4 and 40 while web is traveling in one direction, and contact 15 will bridge 41 and 40 while the web is traveling in the opposite direction. This is to 30 properly regulate the stopping of the web. When the contact 14 comes in contact with 4-40 the current flows through 50-72-40 and 14 to 75, 82, 48, 61 to stopping solenoid 53. Contact 15 would function with the web 35 moving in the opposite direction through 40-15-41-74-82^A 48-61 to stopping solenoid 53. 48 connects with 82 through to 14 for one direction and 82^A through to 15 for 40 the other direction. 48 is controlled by the reversing plunger shaft 83.

Reversing is controlled by levers 17-17, one operated by spool 1 and one by spool 10. Each web-receiving roll is provided with a recess 16 and the lever 17 provided with a 45 disk roller 18, positioned to drop into the recess 16 which is uncovered when the web 11 is entirely unrolled from one spool or the other. When disk 18 drops into recess 16, lever 17 makes contact with contact point 19, 50 completing the circuit which energizes reversing solenoids 8 or 80 which have a common plunger 83. The extension of 83 is connected with a pivoted lever 76 and this by a link 46 with the projecting end 33 of a lever 55 31 pivoted at 32 and connected with the

sleeves 30 which carry the clutch fingers 3. In this way the drive may be shifted from one of the rolls 1 and 10 to the other, and as the web is wound upon these rolls in the same direction and both turn in the same direction, the feed movement of the web is reversed.

When lever 17 makes contact with contact 19, it completes the reversing circuit which energizes solenoids 8 or 80.

65 Drive wheels 26 and 27 idle on their shafts while not engaged to clutch finger 3.

The plungers in solenoids 8 and 80 and 52 and 53 and 55, are of iron the length of the solenoids, and extensions are of brass.

70 47 is a nonconducting material clamped to 83 holding sliding switch 48, which is connected through 61 to stopping solenoid 53.

48 makes alternate contacts with 82 and 82^A to complete the stopping circuit through 75 74 and 75 to contacts 14 and 15 to 40.

What we claim as our invention is:

A street and station indicator comprising a name carrying web, electrically actuated means for feeding said web, and feed stopping means comprising means for de-energizing said electrically actuated means, an electric circuit for operating said de-energizing means, said circuit including two conductors one of which carries the current when 85 the web moves in one direction, the other of which carries the current when the web moves in the other direction, an electrically operated reversing mechanism and a switch operated thereby for switching one or the other of said conductors into the circuit depending on the direction of movement of the web, each of said conductors having a contact finger, a third contact finger in said circuit, a roller turned by the feeding of the web, said 95 roller having two bridge bars extending lengthwise of and at the surface of the roller, said bridge bars being angularly spaced and longitudinally overlapping towards one end, said third contact finger being arranged to 100 engage both bridge bars, and each of the other contact fingers being arranged to engage its respective one of the bridge bars to thereby close the circuit of the feed stopping means.

105 Signed at Seattle, King County, Washington, this 24th day of May, 1926.

THOMAS BRYAN POTHERINGHAM.
MAE McINTYRE.
